[57] CLAIM

The ornamental design for a pushbutton telephone shield plate, as shown and described.

DESCRIPTION

FIG. 1 is a top plan view of a pushbutton telephone shield plate showing my new design;

FIG. 2 is a front elevation thereof;

FIG. 3 is a rear elevation thereof;

FIG. 4 is a right side elevation thereof, the opposite side being a mirror image of the side disclosed;

FIG. 5 is a top plan view of a modified embodiment of the shield plate illustrated in FIG. 1; and

FIG. 6 is a perspective view of the embodiment shown in FIG. 1.
